UNITED STATES PATENT OFFICE.

PHILIP H. FRASER, OF BAYONNE, NEW JERSEY.

DESIGN FOR A SLEEVE-BUTTON OR LIKE ARTICLE.

SPECIFICATION forming part of Design No. 22,697, dated August 15, 1893.

Application filed June 19, 1893. Serial No. 478,172. Term of patent 3½ years.

To all whom it may concern:

Be it known that I, PHILIP H. FRASER, a citizen of the United States, residing at Bayonne, in the county of Hudson and State of New Jersey, have invented and produced a new and original Design for Sleeve-Buttons or Like Articles, of which the following is a specification, reference being had to the accompanying drawings, forming a part thereof, in which—

5 Figure 1 is a plan view of the design applied to a button and Fig. 2 is a sectional view of the same on line 1—1.

10 The essential feature of the design consists of the simulation of a shell, decorated by the representation of a caravel and a rope or cable.

In the drawings A is the head of the button formed with a scalloped beveled margin *a* and with a scroll *b* at its lower edge, through which extend the ends of the cable-like band *c*. The face of the head A within the scallops is 20 sunken and upon it appears the caravel or vessel *d*.

I claim—

The design for a button or like article, substantially as herein shown and described.

PHILIP H. FRASER.
